CALCULATING MACHINE AND TYPEWRITER
COMBINED

René Edmond Boute, Paris, France

Application January 15, 1930, Serial No. 421,035
In France January 18, 1929

3 Claims. (Cl. 235—60)

The present invention relates to improvements in typewriters and calculating machines, whereby texts which involve arithmetical operations as is the case for example in making out bills or like documents may be more rapidly transcribed on the typewriter.

- At the present time, to accomplish this, the operator is obliged to depress the keys of the typewriter to take down the numbers, then the keys of the calculating machine to register therein the figures which are to form the basis of the calculations. The operator then awaits the result which he finally enters on the bill by manipulating the keys of the typewriter.
- 15 The object of the present invention is to simplify this work considerably and the typewriter is accordingly connected to the calculating machine by means of electrical circuits which are closed at the requisite moment by the typewriter, when a figure is entered on the bill or other document to be filled up, electromagnets being mounted in said circuits to control the keys of the calculating machine to register the figures upon which the calculations are based.
- 25 Other characteristics and peculiarities of the invention will become apparent from the ensuing description taken in conjunction with the accompanying drawings wherein:

Figure 1 is a diagrammatic view of a typewriter and a calculating machine of the automatic multiplication type cooperating together in conformity with the invention.

Figure 1—A is a sectional elevation of the typewriter showing certain of the improvements according to the invention.

Figure 1—B is a section through one of the electromagnets operating the multiplicand keys.

Figure 1—C is a section through one of the electromagnets operating the multiplier keys.

40 Figure 1—D is a section through one of the electromagnets operating the corresponding selector bar for one of the groups of electromagnets controlling the keys of the calculating machine.

45 Figure 2 illustrates a circuit arrangement according to the invention for the electrical control of certain keys of the calculating machine by the number keys of the typewriter.

Figure 3 illustrates a contact device fitted to the typewriter for controlling the opening and closing of the electric circuits shown in Figure 2.

Figure 4 illustrates a contact device associated with the number keys of the typewriter for closing first one contact common to all the number

keys and then another contact different for each key.

Figure 5 is a view of a cost sheet on which the calculations performed by the calculating machine are entered by the typewriter.

5 Figures 6 and 7 illustrate respectively in elevation (seen from the rear) and in plan, a constructional modification of the device of Figure 3.

In Figure 1 there has been illustrated diagrammatically a typewriter A and a calculating machine B of the automatic type and of the type similar to the automatic calculating machine illustrated in Patent No. 1,915,037 to H. Suter which issued on June 30, 1933. It will be understood that this Suter patent is here referred to as only one type of automatic calculating machine with which the hereinafter described invention may be combined.

10 The keyboard of the typewriter includes in the customary manner a certain number of keys corresponding to the ten digits.

15 Similarly, the calculating machine B includes a first keyboard m having ten keys and corresponding to the multiplier and a second keyboard M having n rows of keys. Each of the n rows corresponds to a denominational order of the multiplicand and in each row each key corresponds to one of the ten digits; the number of rows varies naturally with the capacity of the machine (in the example illustrated, it has been assumed that there are nine rows only).

20 The result of the operation carried out is registered as usual on the totalizing wheels R. Taking the Suter patent as an example this machine is driven electrically by a motor and is set in operation by a key 71. The multiplicand is set up by depressing of the selected keys A and the multiplier is set up by depressing of the keys B. The machine is then set in motion or operation by 25 the key 71 and the various operations performed as herein provided.

25 In accordance with the invention, the two machines A and B are connected together electrically; the electrical circuit illustrated diagrammatically in Figure 2 comprises out and return wires 4 and 5 respectively. Associated with the principal circuit 4—5 are a plurality of magnets E1, E2, etc. and a rod 25 controlling the operation of the multiplier keys m. Associated with the circuit 4—5 are further magnets EA1, EA2 etc. and circuits 20A, 20B, etc. for controlling the operations of the keys of the multiplicand; there are as many circuits 20A, 20B etc. as there are rows of multiplicand keys (nine in the example 30

illustrated). The circuits 20A, 20B etc. and 25 are controlled by the magnets 21A, 21B etc. The circuit controlled by 21A corresponds to the row *na*, the circuit controlled by 21B to the row *nb*, 5 and so on. All the key actuating circuits are normally open and for one of them to close two conditions must be fulfilled. In the first place, one of the switches C1, C2, etc. must be closed. Each of said switches corresponds to one of the 10 keys of the keyboard of the typewriter (corresponding to the ten digits). Upon depressing any of said keys, the corresponding contact C1, C2, etc. is made.

Another condition upon which the closing of 15 the key actuating circuit depends is that either the contact D shall be closed in the case of the circuit for the multiplier, or one of the contacts Da, Db, etc. in the case of the circuits for the multiplicand.

20 Hence according to the case in point one or other of the electromagnets E1, E2, etc. or EA1, EA2 etc. mounted in said several circuits will be energized. Each of said electromagnets E1, E2, etc. can control a corresponding multiplier key of 25 the keyboard *m* of the calculating machine. The electromagnet E1 controls the key 1, the electromagnet E2 the key 2, and so on.

A certain number of rows of electromagnets EA1, EA2, ... EB1, EB2 ... etc. are provided 30 in the circuits closed by Da Db, etc. Each of said rows of electromagnets corresponds to a row of keys of the multiplicand, and each electromagnet corresponds to a key of the corresponding row. Thus EA1 corresponds to the key 1 of the 35 row *na*, EA2 to the key 2 of the row *na*, EB1 to the key 1 of the row *nb*, and so on. The contacts Da, Db, Dc, Dd are closed automatically when the carriage of the typewriter is displaced.

The circuit arrangement illustrated in Fig. 2 40 is so arranged that stray currents may be eliminated completely. As shown in Fig. 2 the electromagnets EA1, EA2, etc. of a same row are normally not connected directly to the wire leading to the corresponding switch Da. Under these 45 conditions the several rows of electromagnets are not interconnected in normal circumstances. Each of the rows of electromagnets EA1, EA2, etc. is provided with a conducting rod 20A, 20B, etc. capable of oscillating about an insulated pivot 40 and which is normally held by a spring 23a out of contact with the electromagnets EA1, EA2, etc. Each of said rods 20A, 20B, etc. is controlled by 50 an electromagnet 21A, 21B, etc.; the several electromagnets are shunted across a circuit 22 in which is mounted a switch 23 which is closed each time any one of the keys C1, C2, etc. of the typewriter is struck under conditions which 55 will be presently disclosed.

The other ends of the electromagnets 21A, 21B, etc. are connected to the switches Da, Db etc.; when any one of the electromagnets 21A, 21B is energized, it attracts the corresponding rod 20A, 20B etc. through means presently to be described, said rod then making contact with the wire 24 60 likewise connected to the corresponding switch Da, Db, etc. Similarly a rod 25 is provided for the row of electromagnets E1, E2, etc. corresponding to the keys of the multiplier of the calculating machine.

65 In order that by depressing one of the keys of the typewriter the corresponding contact C1, C2, etc. and the switch 23 shall be closed in proper sequence, the arrangement illustrated in Fig. 4 may be adopted, according to which the end 26 70 of each key carries two fingers 27 and 28 capable

of acting respectively on pins 29 and 30, the first of which when depressed closes the corresponding contact C1, C2, etc., and the second the contact 23. Preferably the fingers 27 and 28 will be of such length that the contact 23 shall be made first. Similarly the member 30 may be common to all the keys, since the switch to which it corresponds has to be closed each time a key is depressed.

Finally there has been illustrated in Fig. 3 a 10 plan view of the lay out of the contact studs controlled by the typewriter on which are mounted the contact studs *pa*, *pb*, etc. (one contact stud for each row of electromagnets EA1, EB2, etc.). On account of the fact that it moves with the carriage, the contact studs PM mounted on the bar 10 connected to the electrical circuit, can make contact in succession with the contact studs *pi*, *ph*, etc. On the block II is mounted the contact stud *pm* for controlling the multiplier, said 15 stud cooperating with the movable stud PM mounted on the bar 10. The stud *pm* corresponds to contact D in Fig. 2. There is moreover provided a contact stud 32 for controlling the multiplier bar 1a of said machine.

20 The device operates in the following manner:

Assuming, as illustrated diagrammatically in 25 Fig. 5, that a bill has to be made out which, as usual, comprises a first column in which is entered the price per unit of the object, a second column giving the number of these objects, a third column to designate them, and finally, a fourth for a total, the bill is inserted in the typewriter in the usual manner. To commence writing, the machine must strike opposite the first column. 30 The position of the bar 10 is then determined so that at this instant the contact stud PM shall be opposite the contact stud *pt*. The contact *pt* is then closed: If at this instant the key corresponding to the first digit of the price per unit 35 (that is to say the multiplicand) is depressed, the corresponding contact C1, C2, etc. will be made. The corresponding electromagnet EI1, EI2, etc. will be energized, and the corresponding multiplicand key of the row *ni* actuated. The first digit 40 of the multiplicand will have been thus set up on the calculating machine.

When the second digit of the price per unit is to be set up, the contact stud PM will be opposite the contact stud *ph*, and when the key corresponding to the second digit is depressed, a contact C1, C2, etc. will be closed again whereby a key of the second row *nh* of the multiplicand will be actuated. If the price per unit has four digits, a key in each of the rows *ni*, *nh*, etc. will be 45 actuated. When the operator depresses any one of the keys of the typewriter (number keys of course), such key first closes the contact 23 whereby the electromagnets 21I, 21H, etc. can be energized, then the corresponding contact C1, C2, etc. 50 so that only the corresponding electromagnet 21I, 21H etc. will be energized to attract the corresponding conducting rod 20I, 20H, etc. Under these conditions, only the electromagnet EA1, EA2, etc. corresponding to the contact C1, C2, etc. 55 and to the switch Da, Db, etc. closed at this instant due to the position of the carriage of the machine, will be energized and will control the corresponding key of the calculating machine.

60 It will be observed that by having insulated the several vertical rows of electromagnets EA1, EA2, etc. it has been possible to completely eliminate stray currents between the several rows.

65 It is obvious that other arrangements of studs 70

may be provided, if it is desired, to use this device with other machines.

Another improvement is provided to obviate the following drawback: whereas the electromagnets EA1, EA2, . . . EB1, EB2 . . . etc. can only be energized on two conditions, namely that a switch C1, C2, etc., and a switch Da, Db, etc. shall be closed, the electromagnets corresponding to the contact studs at 32 which operate control keys 10 are energized as soon as the corresponding movable stud comes opposite them.

Under these conditions, the electromagnets might be energized both when the carriage shifts in the operative direction and when it shifts in 15 the opposite direction; now only the first of these energizations is necessary; to prevent the second, a switch 37 is inserted in the circuit 36, in which are mounted, for example, in parallel the various electromagnets, said switch 37 being 20 closed at each operation of the tabulator of the typewriter to shift the carriage when a bill is made out. A device similar to that of Fig. 4 may be provided to permit the tabulator key to operate the switch 37. The tabulator in question will 25 be of a well known type, preferably a decimal tabulator and need not be described here. Said decimal tabulator generally comprises a certain number of keys corresponding to the units, tens, hundreds, thousands, tens of thousands . . . orders. Depending on the highest denominational 30 order of the first digit of the number to be set up, one has only to depress the desired key of the tabulator. By depressing this key the contact 37 is closed so that the circuit can be closed 35 through the circuit of the stud, as 32, with which the corresponding movable stud on the bar 18 happens to be in contact at the moment. On the other hand, when the carriage of the typewriter is shifted by hand, the switch 37 will always 40 remain open so that when the movable studs pass over the fixed stud, as 32, the electromagnets mounted in the circuit 36 will not be energized.

In Figs. 6 and 7 have been illustrated an improvement in the arrangement of the studs in the typewriter. According to this improvement, the block II of Fig. 3 is replaced by independent blocks IIa, IIb, etc. each carrying one of the sets 45 of contact studs. The block IIa will carry for example the set of studs pi, ph, etc.; the block 50 IIb will carry the set pm, 32.

Said blocks IIa, IIb etc. are formed by a block of insulating material at the two ends of which are mounted cheeks 45 forming cursors whereby they may be mounted in grooves of a rack 46 55 fixed in any suitable way on the frame of the typewriter. With this particular mounting, each block IIa, IIb etc. may be fixed on the frame of the machine in this or that position. As the various sets of contact studs carried by the frame 60 of the machine may be thus offset, it is no longer necessary to offset the studs PM, Pm, 38 etc. which shift with the carriage; as a simplification, all these studs may be replaced by a single stud 47 carried directly by the carriage. Said contact 65 stud 47 will first come into contact with the studs of the block IIa, then with those of the block IIb and so on. Thus by suitably offsetting these various blocks, the circuits can be controlled in the same manner as previously.

I claim:

1. In a device for combining together a typewriter and a calculating machine, a plurality of electric circuits, a first set of circuit closing means adapted to be actuated by the respective number keys of said typewriter, a second set of circuit closing means including members controlled by the traversing portion of said typewriter in predetermined positions thereof, a plurality of electromagnets mounted in rows, the several electromagnets of a row being normally isolated from each other, and means controlled by said second set of circuit closing means for simultaneously connecting together the electromagnets of a row, whereby, by closing one of each of said two sets of circuit closing means, a circuit is established through the electromagnet corresponding to the two circuit closing means operated.

2. In a device for combining together a typewriter and a calculating machine, a plurality of electric circuits, a first set of circuit closing means adapted to be actuated by the respective number keys of said typewriter, a second set of circuit closing means including members controlled by the traversing portion of said typewriter in predetermined positions thereof, a plurality of electromagnets mounted in rows, the several electromagnets of a row being normally isolated from each other, a conducting bar located in spaced relation to each row of electromagnets, a second group of electromagnets each energized by closing one of each of said two sets of circuit closing means, each of said last mentioned electromagnets when energized actuating the corresponding conducting bar to connect with the corresponding row of said first mentioned electromagnets, whereby one of said latter electromagnets is energized to actuate a key of said calculating machine.

3. In a device for combining together a typewriter and a calculating machine, a plurality of electric circuits connecting said typewriter to said calculating machine, a set of switches mounted in said respective circuits and adapted to be actuated respectively by the number keys of said typewriter, means mounted on said typewriter and adapted to be adjustably fixed in position, said means including a number of contact studs, a member carried by the traversing portion of said typewriter and adapted to contact successively with said contact studs, a plurality of electromagnets mounted in rows, the electromagnets of a row being normally isolated from each other, a conducting bar associated with each row of electromagnets, a plurality of relays each adapted to be energized by simultaneous actuation of any one of the number keys of the typewriter and contacting of said member with the contact stud corresponding to the relay, each relay when energized attracting one of said conducting bars which thereby closes one of said circuits through the electromagnet of its row corresponding to the number key actuated, said electromagnets when energized being adapted to actuate the keys of said calculating machine.

RENÉ EDMOND BOUTET.
